DESIGN.

—o—

W. T. GOUCH.

CARPET.

No. 17,766.

Patented Oct. 11, 1887.

UNITED STATES PATENT OFFICE.

WILLIAM T. GOUGH, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,766, dated October 11, 1887.

Application filed August 30, 1887. Serial No. 248,315. Term of patent 3½ years.

To all whom it may concern:

Be it known that I, WILLIAM T. GOUGH, of Yonkers, county of Westchester, and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is made up of a body part and a border.

The main feature of the body part is the arrangement upon a continuous stem-work of 20 a large bell-shaped flower and compound leaves, the intervening spaces being ornamented with small flowers and leaves scattered irregularly over the face of the carpet, and also with outline or skeleton leaf and flower 25 forms of less prominence in the pattern.

A is one of the large bell-shaped flowers, and has two distinct circles of leaves surrounding the heart of the flower.

B is another bell-shaped flower, at the center of which are a number of little flower-heads supported on slender stems. Around this center are two circles of leaves.

C is a compound leaf with corresponding lobe-like leaves or part leaves on either side.

D is another compound leaf or cluster of 35 leaves, with ends of the leaves curved over, so as to show their under side. The outline leaf and flower work is ornamented at certain parts by parallel lines or partial lattice-work.

My border E has an inner ornamented margin. 40 Its middle portion is ornamented with large bell-shaped flowers A and compound leaves C, similar to those already described. Between these figures are smaller leaves and stems, and also outline or skeleton leaf and 45 flower forms ornamented with parallel lines or a partial lattice-work. The outer margin of the border is ornamented with tall stems supporting bulb-like forms, with series of lines and small flowers scattered over them, and 50 with fan-shaped forms.

What I claim as new, and desire to secure by Letters Patent, is—

1. In a design for a carpet, the figures A, B, C, and D and the other figures of the body 55 portion, substantially as shown.

2. In a design for a carpet, the border portion E, substantially as shown.

3. The design for a carpet, consisting of the figures A, B, C, and D and the other figures 60 of the body portion, and the border portion E, substantially as shown.

WM. T. GOUGH.
